UNITED STATES PATENT OFFICE.

DONALD DONALD, OF SYDNEY, NEW SOUTH WALES, AUSTRALIA.

DOOR LOCK.

Application filed October 10, 1921. Serial No. 506,796.

To all whom it may concern:

Be it known that I, DONALD DONALD, a subject of the King of Great Britain and Ireland, residing at Rushcutters Bay, Sydney, New South Wales, Australia, have invented certain new and useful Improvements in Door Locks, of which the following is a specification.

This invention relates to door locks of 10 the type having a tubular casing, and the object of the invention is to effect certain improvements whereby (a) the length of the casing can be reduced so that it can be fitted to light cheap doors having narrow 15 stiles, (b) whereby the cost of manufacture is reduced, and (c) whereby the springs controlling the moving parts are strengthened thus increasing the efficiency and adding to the life of the lock.

20 A further improvement is that the handles which operate the lock bolt are rendered silent in operation.

The improved lock is constructed in two longitudinal sections hereinafter referred 25 to as A and B which are adapted to be placed and held together to form a complete tubular cased lock, with spring controlled bolt C, locking mechanism D, and operating handles E.

30 Referring to the drawings which illustrate the improved lock,

Figure 1 is a perspective view of lock section A with movable parts removed therefrom.

35 Figure 2 is a similar view of lock section B.

Figure 3 is a plan of lock bolt C removed from casing.

40 Figures 4 and 5 are perspective views of the sliding and rocking plates respectively which form the bolt locking mechanism D.

Figure 6 is a sectional elevation of lock section A showing slide locking plate Figure 4 in position.

45 Figure 7 is a section through line r—r Figure 6.

Figure 8 is a side elevation of lock section A showing slide plate Figure 4 and rocking plate Figure 5 in position.

50 Figure 9 is a side elevation of lock section B with spring controlled bolt C removed therefrom.

Figure 10 is a section through line p—p Figure 9 showing bolt C in position.

55 Figure 11 is a sectional plan showing complete lock fitted in door stile.

Figure 12 is a cross section of lock on line s—s Figure 11.

Figure 13 is a section through line v—v Figure 11.

60 Figure 14 is a perspective view of the assembled lock ready for fitting in door stile.

Figure 15 illustrates a key suitable for operating the locking mechanism D.

The casing of lock section A is a one 65 piece metal casing semi-circular in cross section having at one end an anchor plate 15 with bolt aperture 16 and screw holes 17. The other end of casing has a semi-circular plate 18 with projecting tongue 19. A portion of the interior of the casing is thickened to form a flat bed plate 20 in which is formed a recess 21 adapted to house a coil spring 22. A stud 23 projects from the bed plate 20, and segmental key wards 24 are provided on each side of a key way 25 to cut into the wall of the casing.

Between the end wall 18 and the bed plate

20 a rectangular aperture 26 is formed in the casing wall. The locking mechanism 80

D which fits within lock section A consists of a sliding plate 4 and an oscillating plate 5. The plate 4 has a bracket 27 projecting from its under face, a stud 28 projecting from its upper face and an open slot 29.

85 The plate 4 fits into section A as shown in Figures 6, 7, 8 and is held in its normal position by coil spring 22 in recess 21 which bears against the bracket 27. The plate 4 can only be moved from its normal position by the action of a key bearing against its curved edge 30.

80 The oscillating and locking plate 5 which is rotatably mounted on the stud 23 has a rearwardly projecting locking piece 31 and downwardly projecting locking piece 32, and a bifurcated curved front edge 33 which is adapted to be engaged by a key to oscillate the plate in either direction, for the purpose and in the manner

90 hereinafter explained.

95 The lock casing B is similar in cross section to casing A and both casings A and B with their internal fittings are adapted to be assembled as shown in Figure 14 to form a tubular lock. The casing B has projecting 100

segmental key wards 34, and aperture 35 so positioned that when the sections are assembled they directly oppose the key wards

24 and aperture 26 in casing A. A right 105 angular bracket 36 projects from the inner wall of casing B. The locking bolt C illustrated in Figure 3 fits into casing B as

110

shown in Figure 10, and is held in its normal projected position by a coil spring 37 which bears between the fixed bracket 36 in casing B and cross studded partition 38 on bolt C. A stud 50 projects inwards from the bolt C and is so positioned as to be engaged when desired by the oscillating plate 5 of the locking mechanism D for the purpose of securing the bolt in the projected or withdrawn position. The rear end of the bolt C is in the form of a disc 39 which is movable in the rear portion of the tubular casing formed when the sections A and B are assembled by the operation of pivoted lever handles E.

The operating ends 44 of handles E which are pivoted at 40 in anchor plates 41 pass through holes 42 in door stile 43 and enter the tubular casing of the lock through the opposing apertures 26 and 35 therein, so as to engage the disc 39 to operate the bolt C inwards against the pressure of spring 37 as illustrated in Figures 11 and 13. Rubber sleeves 45 are provided on the short arms 44 in order to deaden any sound that may be caused by making contact with the disc 39. The operation of the locking mechanism is as follows:—Normally the bolt C is free to be moved backwards or forwards for the reason that the stud 50 which projects therefrom has an unobstructed path of travel. When it is desired to lock the bolt C in the projected position the oscillating plate 5 is rotated to bring the projection 32 thereon into the path of the stud 50 on bolt C as shown in Figure 8. This is accomplished by a key 51 with clefts 52 adapted to engage the wards 24 and 34 which after being inserted through the keyway 25 is adapted on rotation to first move the slide plate 4 rearwards thus freeing the oscillating plate 5 from engagement with the stud 28 and enabling the key on being further rotated to oscillate the plate 5 in either direction so as to bring the projection 31 thereon into position either above or below the stud 28 on plate 4. As soon as the key loses contact with the plate 4 the plate springs back into its normal position and holds the plate 5 in its set position either out of or in the path of the stud 50. The case sections A and B are held together when assembled by a metal clasp 53, and prevented from moving laterally by tongues 55 which engage corresponding slots in the opposing sections.

I claim.

1. An improved door lock comprising a

casing constructed in two longitudinal sections adapted to be fitted together to form 60 a tube, a sliding bolt mounted within one of the case sections and adapted to be held in the normal position by a coil spring, pivoted lever handles which pass through opposing apertures in both case sections, mechanism for locking the said bolt mounted in the opposing case section and adapted to be actuated by a key, opposing key ways and circular key wards in each of the case sections, and an anchoring plate with bolt 70 aperture therein on one of the case sections substantially as and for the purpose herein set out.

2. An improved tubular lock for doors comprising a longitudinally divided outer tubular casing having a face plate, key apertures and lever apertures and a bolt having a projecting stud within said casing actuated outwards by a spring bearing against a fixed bracket, and inwards by pivoted levers having rubber sleeves adapted to bear against its rearward end; and a bolt locking mechanism consisting of a sliding plate with a spring and a projecting stud, an oscillating plate adapted to be moved 85 about a fixed pin into or out of the path of the first mentioned projecting stud substantially as herein described and illustrated in the drawings.

3. A door lock comprising a tubular lock 90 casing constructed in two corresponding longitudinal sections adapted to be fitted together each of which is semi-circular in cross-section and has at one end a semi-circular end plate and one of which has at 95 the other end an anchor plate formed with a bolt aperture and screw holes, a portion of the interior of one of said sections being thickened to form a flat bed plate in which is formed a recess adapted to house a coiled 100 spring, and a rectangular aperture between the bed plate and the semi-circular end plate and the other section of which is formed with a rectangular aperture opposed to the rectangular aperture in said first mentioned 105 section and with a projecting bracket at the forward end of said aperture, both of said sections having segmental key wards provided on each side of a key way cut in the wall of the casing.

In testimony whereof he has affixed his signature in presence of two witnesses.

DONALD DONALD.
